UNITED STATES PATENT OFFICE

2,506,714

CLIPPER

Alva R. Ferree, Sr., Perrysburg, Ohio

Application November 25, 1946, Serial No. 712,070

2 Claims. (Cl. 30—245)

1

This invention relates to new and useful improvements and structural refinements in clippers, and the principal object of the invention is to provide a device of the character herein described, such as may be conveniently employed for a variety of purposes, namely, for the trimming of lawns and hedges, for pruning trees, and for other uses of a similar nature.

A further object of the invention is to provide a clipper which is of simple construction and which may be easily and conveniently manipulated.

Another object of the invention is to provide a clipper which is novel in appearance and which will readily lend itself to economical manufacture.

An additional object of the invention is to provide a clipper which may be readily disassembled for purposes of inspection or repair.

With the above more important objects in view, and such other objects as may become apparent as this specification proceeds, the invention consists essentially of the arrangement and construction of parts as illustrated in the accompanying drawings, in which:

Figure 1 is an elevational view of the invention.

Figure 2 is a cross sectional view of a handle used in the same.

Figure 3 is a cross sectional view, taken substantially in the plane of the line 3—3 in Figure 1.

Figure 4 is a top plan view of the device shown in Figure 1.

Figure 5 is a cross sectional view, taken substantially in the plane of the line 5—5 of Figure 1, and

Figure 6 is a perspective view of one of the cutting jaws used in the invention.

Like characters of reference are used to designate like parts in the specification and throughout the several views.

Referring now to the accompanying drawings in detail, the invention consists of a clipper designated generally by the reference character 10, the same embodying in its construction a substantially U-shaped handle 11 provided in the side members 12 thereof with a pair of opposed, longitudinally extending channels or ways 13.

These ways slidably receive a finger grip 14 and a pair of co-acting cutting jaws 15 are pivotally attached to this finger grip by means of a suitable pin 16.

It is believed that the configuration of the finger grip 14 will be clearly apparent from the accompanying drawings and it will be noted that the jaws 15 are each provided with a suitable aperture 17, adapted to receive the aforementioned pivot pin.

2

The free end portions of the side members 12 are transversely slotted as at 18, the slots 18 being aligned with the ways 13 and being adapted to receive the end portions of a pair of links 19. 5 These links are pivotally secured in position by means of suitable pins 20, as will be clearly understood.

The free end portion of each of the links 19 is pivoted as at 21 medially the length of one of 10 the aforementioned jaws 15, this pivoted connection being hereinafter more fully described.

A suitable spring 22, formed from a resilient wire-like rod, is coiled medially of its length to provide an eye 23, the latter being disposed adjacent the aforementioned pin 16. It will be noted however, that there is no direct connection between the pin 16 and the eye.

The free end portions 24 of the spring 22 are arcuated somewhat and each portion is anchored 20 in a suitable aperture provided in the free end portion of the adjacent limb 19 and in a further aperture 25 provided in each of the jaws 15. In this manner, the links 19 are pivoted to the jaws, as has been already explained.

25 When the invention is placed in use, the resiliency of the spring 22 will normally urge the jaws 15 into their separated position, as shown in Figure 1. However, by grasping the mid-portion 26 of the handle 11 and pressing the finger grip 14 in the direction of the arrow 27, the jaws 15 will be brought together, as indicated by the arrows 28.

30 The cutting edges of the jaws are indicated by the reference character 29 and it should, of course, be understood that jaws of various sizes and types may be employed in accordance with different working conditions.

In order to prevent the side members 12 of the handle 11 from spreading, a tie rod 30, configured substantially as shown, may be employed, the same being attached to the side members 12 by means of the aforementioned pins 20.

40 It is believed that the advantages and use of the invention will be clearly understood from the foregoing disclosure and accordingly, further description thereof at this point is considered unnecessary.

45 While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. In a clipper, the combination of a substantially U-shaped member including a pair of spaced side portions constituting guides and a bight portion forming a handle, a transverse finger piece slidably engaging said guides and movable toward and away from said handle, a pair of coacting jaws having outer and inner end portions, a common pivot attaching the inner end portions of said jaws to said finger piece, and a pair of links each pivoted to the outer end portion of one of said jaws and to one of said guides, whereby said jaws are drawn together by sliding said finger piece toward said handle.
2. The device as defined in claim 1 wherein said

guides are formed with a pair of opposing grooves to slidably receive lateral edge portions of said finger piece.

ALVA R. FERREE, SR.
